(57) **CLAIM**

The ornamental design for a gland nut, as shown and
described.

DESCRIPTION

FIG. 1 is a rear perspective view of the gland nut of the present
invention.

FIG. 2 is a side plan view of the gland nut of the present
invention.

FIG. 3 is a front plan view of the gland nut of the present
invention.

FIG. 4 is a rear plan view of the gland nut of the present
invention.

FIG. 5 is a side plan view of the gland nut of the present
invention.

FIG. 6 is a front perspective view of the gland nut of the
present invention; and,

FIG. 7 is a cross sectional view taken along line 7-7 on FIG.
4.

The broken line portion of the Figures is included to show
unclaimed subject matter and forms no part of the claimed
design.

1 Claim, 4 Drawing Sheets
